LINK CHAIN

Michael Chernow, New York, N. Y.

Application October 29, 1952, Serial No. 22,039

Term of patent 7 years

(CL. D45—16)

To all whom it may concern:

Be it known that I, Michael Chernow, a citizen of the United States and residing at New York, in the county of New York and State of New York, have invented a new, original, and ornamental Design for Link Chain, of which the following is a specification, reference being had to the accompanying drawings, forming part thereof, and in which

Fig. 1 is a top plan view of a link chain, showing my new design, with a portion thereof broken away for convenience of illustration,

Fig. 2 is a side elevational view of a portion of the chain shown in Fig. 1, and

Fig. 3 is a transverse sectional view thereof taken along the line 3—3 of Fig. 1.

The dominant feature of my design resides in the elements disclosed in full lines, said elements

being repeated throughout the length of the link chain, as indicated by the broken line illustration.

I claim:

The ornamental design for a link chain, substantially as shown and described.

MICHAEL CHERNOW.
